UNITED STATES PATENT OFFICE.

CHILION M. FARRAR, OF BUFFALO, NEW YORK.

DESIGN FOR A STEAM-ENGINE.

SPECIFICATION forming part of Design No. 12,149, dated February 8, 1881.

Application filed June 29, 1880. Term of patent 14 years.

To all whom it may concern:

Be it known that I, CHILION M. FARRAR, a citizen of the United States, residing in Buffalo, in the county of Erie and State of New York, have invented and produced a new and original Design for a Steam-Engine, of which the following is a specification, reference being had to the accompanying drawings, forming a part thereof.

10 Figure 1 is a front view of my newly-designed engine. Fig. 2 is a side elevation of the same, and Fig. 3 represents a horizontal section through line xx of Figs. 1 and 2, these three views being deemed necessary to fully illustrate my design.

15 My design represents a vertical or upright engine, A being the cylinders, of usual form, arranged on a frame, B, which is a hollow case, open at the front, and provided with two ribs, 20 C C, arranged parallel, so that the frame is of the same width from the top to the bottom of said ribs. The front and back of the frame are inclined or flaring, as shown in Fig. 2, so that the top D, when it meets the cylinder, is round, 25 and the bottom, at E F G, is in the form of an

oval, (see Fig. 3,) while the base-plate I is in the form of a rectangle. The front or open part of the frame is in the form of a pointed arch at the top and bottom J K, (see Fig. 1,) and is made to incline back until it meets the 30 ribs at L, where it is made straight a sufficient distance to receive the slides M. At each side of the lower part of the frame F are two curved ribs, N N; and O represents an arch, one on each side of the frame, provided with a molding, P.

I claim—

35 The design for a steam-engine herein shown and described, consisting of a vertical engine having the upper part of the frame round 40 where it joins the cylinder, its sides parallel, the lower part, F, in the form of an oval resting on a base, I, and the opening in front terminating in pointed arches J K at the top and bottom, substantially as described.

CHILION M. FARRAR.
